UNITED STATES PATENT OFFICE.

WILLIAM H. KIDDER, OF NEW YORK, N. Y.

WINDOW-WASHER.

SPECIFICATION forming part of Letters Patent No. 772,716, dated October 18, 1904.

Application filed March 21, 1904. Serial No. 199,292. (No model.)

To all whom it may concern:

Be it known that I, WILLIAM H. KIDDER, a citizen of the United States, residing at New York, in the county of New York, State of New York, have invented certain new and useful Improvements in Window-Washers, of which the following is a specification, reference being had therein to the accompanying drawings.

10 This invention relates to window-washers, and particularly to a reservoir having a feed-opening to coöperate with the washer.

The invention has for an object to provide a reservoir having a reduced discharge portion disposed at an angle to the vertical axis of the reservoir and provided with an outlet adjacent to a rubbing material adapted to perform the washing operation whereby the movement of the reservoir in the act of washing the window causes a portion of the body of liquid therein to be projected automatically through the discharge-opening directly upon the window to be cleaned.

Other and further objects and advantages of the invention will be hereinafter set forth and the novel features thereof defined by the appended claim.

In the drawings, Figure 1 is a perspective of the invention; Fig. 2, a central vertical cross-section on line 2 2 of Fig. 3; Fig. 3, a vertical central longitudinal section on line 3 3 of Fig. 2, and Fig. 4 a sectional detail of the discharge-passage from the reservoir.

Like letters of reference refer to like parts in the several figures of drawings.

The letter A designates a reservoir which may be of any desired material or configuration, but is preferably V-shaped, as shown, having at one side a discharge-passage A', 40 having side walls converging toward the upper end thereof, where it is provided with an opening A². The opposite side of the V-shaped reservoir is likewise formed with converging side walls, as shown at A³, and provided with a filling-opening A⁴, suitably closed, while intermediate of the reduced portions A' and A³ a tubular socket A⁵ is pro-

vided to receive a pole or other support by which the washer is manipulated.

The discharge portion A² is provided at its upper outer face with a washing material of any desired character, preferably felt, as shown at B, which may be removably held in position by means of a clasp B', secured to the outer wall of the reservoir and provided with thickened outer edges B², between which the felt B is disposed and secured by any desired means—for instance, a cross-pin B³, as shown in Fig. 2.

The opposite wall A³ of the V-shaped portion is provided upon its upper edge with a holder C, adapted to receive a drying-strip C', preferably of rubber, which is retained in position by the inwardly-bent edge C², so that it can be removed and replaced whenever found necessary or desirable.

In the operation of the invention the reservoir is filled with water, from which there is no escape except through the feeding action, which is accomplished in the reciprocation or other movement of the washer during the washing operation. It will be seen that, at such times the washer is inclined toward the window, and the greater body of water within the discharge side of the reservoir will be given an independent motion at the time when the direction of movement of the reservoir is changed, which will project a portion thereof through the opening A² above the washing material, so as to directly apply the necessary liquid at the desired point of application, while at all other times the reservoir may be safely handled without danger of leakage.

When it is desired to dry the window, it is only necessary to reverse the position of the parts and bring the drying-strip into action, which when in its inclined position for that purpose carries the body of water sufficiently away from the discharge-passage to prevent any accidental escape therethrough.

It will be obvious that changes may be made in the details of construction and operation without departing from the spirit of the invention as defined by the appended claim.

Having described my invention and set forth its merits, what I claim, and desire to secure by Letters Patent, is—

In a window-washer, a V-shaped reservoir provided at its upper portion with oppositely-diverging separated receptacles, one having its side walls converging toward each other at their outer ends and there provided with a discharge-opening, a washing-strip carried by

the outer wall of the reservoir adjacent to said opening, and a drying-strip carried by the upper portion of the opposite receptacle. 10

In testimony whereof I affix my signature in presence of two witnesses.

WILLIAM H. KIDDER.
